DESIGN FOR IMITATION LEATHER OR SIMILAR ARTICLE

Jac Corwin, Brooklyn, N. Y.

Application December 5, 1935, Serial No. 59,926

Term of patent 7 years

To all whom it may concern:

Be it known that I, Jac Corwin, a citizen of the United States, residing at Brooklyn, in the county of Kings and State of New York, have invented a new, original, and ornamental Design for Imitation Leather or Similar Article, of which the following is a specification, reference being had to the accompanying drawing, forming a part thereof.

The figure is a plan view of a piece of imitation leather showing my new design, the same constituting the design unit.

The characteristic feature of the design resides in the promiscuous arrangement of letters of the alphabet in raised relation to the background of the article.

I claim:

The ornamental design for imitation leather or similar article, substantially as shown and described.

JAC CORWIN.
